[57] CLAIM

The ornamental design for a beverage cup, as shown
and described.

DESCRIPTION

FIG. 1 is a front elevational view of a beverage cup
showing my new design, the rear elevational view is a
mirror image thereof;

FIG. 2 is a left side elevational view thereof;

FIG. 3 is a right side elevational view thereof;

FIG. 4 is an enlarged fragmentary view of the sculp-
tured portion within the broken line area of FIG. 2;

FIG. 5 is an enlarged fragmentary cross-sectional view
taken on line 5—5 of FIG. 4;

FIG. 6 is an enlarged fragmentary cross-sectional view
taken on line 6—6 of FIG. 4.

FIG. 7 is a top plan view thereof; and

FIG. 8 is a bottom plan view thereof.
